UNITED STATES PATENT OFFICE.

DANIEL LAPE, OF FORT THOMAS, KENTUCKY.

STOVE OR FURNACE.

1,234,039.

Specification of Letters Patent. Patented Mar. 16, 1920.

Application filed March 25, 1918. Serial No. 224,540.

To all whom it may concern:

Be it known that I, DANIEL LAPE, a citizen of the United States, and a resident of Fort Thomas, in the county of Campbell and State of Kentucky, have invented certain new and useful Improvements in Stoves or Furnaces, of which the following is a specification.

My invention relates to stoves or furnaces for burning solid fuel or gas, and its object is to combine in one apparatus means for burning either solid fuel, such as coal, or for burning gas, or for burning both the solid fuel and the gas at the same time; and to thereby obtain a maximum amount of heat from either or both sources without interference with the combustion of either form of fuel. Another object of my invention is to provide means for conveniently adapting the apparatus especially to burn either form of fuel, and to provide for an efficient radiation when either form of fuel is used alone. A further object of my invention is to provide such apparatus at a minimum of first cost and cost of installation; and to provide for converting into such apparatus furnaces originally designed only for burning solid fuel.

My invention consists in the combination of parts and in the details of construction and arrangement of parts as will hereinafter be more fully described and claimed.

In the drawings:

Figure 1 is a general perspective view taken from the front and illustrating a furnace in which my invention is embodied, parts of the furnace being represented as broken away and omitted in order to more readily reveal certain details of my invention;

Fig. 2 is a similar view taken from the rear;

Fig. 3 is a horizontal cross-section on a plane corresponding to the line 3—3 of Fig. 1, showing the apparatus adjusted for burning both kinds of fuel; and

Fig. 4 is a partial cross-section similar to Fig. 3, but showing the apparatus adjusted for burning solid fuel only.

The furnace which I have chosen for the purpose of illustrating the preferred construction and mode of use of my invention comprises the ash-pit 1 having the clean-out and draft opening 2 at the front, which is closed by a door 3 (Fig. 3); the fire-pot 4

having the grate 5 and supported on top of the ash-pit and supporting the dome 4' which has the fuel-intake opening 6 at its front, which is closed by a door 7 (Fig. 3); and this dome 5 being surmounted by the 60 radiator 8 having at its front a clean-out opening 9 closed by a door 10 (Fig. 3.)

This radiator 8 in this kind of furnace comprises a central intake part 11 fitting over the opening in the top of the dome 4' 65 where the radiator 8 rests on the dome, and having a forwardly extending short flue 12 leading into a large annular outer flue 13 that passes all around the central part 9 and has at the back the outlet flue 14, which 70 it will be understood leads to the chimney for carrying the smoke and other products of combustion to the outer air.

The fire-pot 4 and dome 4' thus make up a solid-fuel combustion chamber, and the 75 grate 5 a means therein for burning solid fuel, such as coal, coke, wood or any other solid fuel desired to be burned, and to which the parts may be adapted in any well known manner.

The ash-pit 1 is surrounded by a suitable base 15 on which is supported the casing 16 which, with the furnace front 17 (Fig. 3,) entirely surrounds the parts just described. The front openings 2, 6 and 9 open through 80 the front 17, and the outlet flue 14 leads out through the rear side of the casing. The top of the casing is closed except where the warm-air pipes 18 (shown in Figs. 1 and 2 by dotted lines) lead from it in various directions to distribute the air from the inside of the casing to various parts of the house or other place that is to be heated. The air is drawn into the casing for leading through the duct 19 (shown in Figs. 1 and 2 by 85 dotted lines) leading through the casing-wall near its bottom at the rear. All of these parts just described, being old and well known, need no further illustration or description.

The only ones of the parts of the solid fuel furnace just described that require any modification at all, are the radiator 8 and casing 16, which modifications are comparatively slight, as will be set forth hereinafter.

As will be clearly seen in Figs. 3 and 4, the sides of the casing 16 are spaced some distance outwardly from the outside of the radiator 8 for the free circulation of air around it as well as through the inner open-

ing of the radiator where the large outer annular flue 13 is spaced away from the inner part 11 of the radiator. This radiator 8 is therefore of somewhat greater diameter than the dome 5, fire-pot 4 and ash-pit 1 in this kind of furnace; and with the spacing of the casing-wall still farther outward, considerable space is left all around the lower part of the furnace below the radiator 8 except at the front where the parts 2, 6 and 9 lead forward from the ash-pit 1, dome 5 and radiator 8, respectively, as is necessary in order to permit access to the interior of these parts for reasons well known, and as indicated by the names given to them in the foregoing description.

In the preferred embodiment of my invention, therefore, I prefer to use this kind of furnace construction, because it leaves ample spaces at the sides and rear of the solid-fuel-burning part of the furnace under the radiator thereof for the installation of the means for burning gas.

Thus, I provide upright casings or chambers 20 in these spaces, each of a horizontal cross-section that is of segmental shape at the rear and extends substantially straight from the segmental part toward the front, and having its front side 21 curved to fit snugly against the inside of the front part of the wall of the casing 16 at that side and having its rear end 22 spaced some distance laterally from the front-to-rear center line of the furnace at the rear thereof and preferably extending about parallel with that line. Thus, the two chambers 20 extend from opposite sides of the draft and fuel openings 2 and 6 at the front, around behind the solid-fuel-burning part of the furnace, where the rear ends 22 are spaced apart far enough to leave an air passage 23 between them. Also these chambers 20 are made of such width relative to the spaces they occupy that they leave between their inner sides and the inner solid-fuel-burning part of the furnace inner air-spaces 24, and between their outer sides and the sides of the casing 16, outer air-spaces 25. Also, these chambers 20 are made of such height relative to these spaces that they leave above them, between their tops and the bottom of the radiator 8, upper air-spaces 26. Also, preferably, these chambers are supported a short distance up from the base 15 so that some air-space 27 is left under each chamber 20. Thus, each chamber is entirely surrounded above, below, inside and outside by air spaces inclosed by the casing 16 and the inner and outer spaces communicate at the rear through the passage 23 adjacent to the duct 19 through which the cold air enters the casing 16.

Where the front 21 of each chamber 20 is against the wall of the casing 16, a suitable opening 28 is provided through the

casing-wall and the front 21 near the bottom so that access is had to the lower part of the chamber 20. In this lower part is a gas burner 29, which, as here shown, consists of two tubes 30 branching from a mixer 31 at the front and extending along substantially parallel to each other in conformity with the curving shape of the chamber cross-section and meeting in a U-bend 32 at the rear; each tube having a plurality of perforations 33 of suitable size and shape and emitting the gas for proper combustion after having been mixed with a suitable proportion of air at the mixer 31; the proper proportion and arrangement of these orifices 33 and of the mixer 31 in themselves being readily determined by those skilled in the art. However, it is preferable that in locating the orifices 33 they be directed convergingly from the parallel tubes 30 and from the U-bend 32 so that the flames will not strike the sides of the chamber; thus lessening their destructive effect on the chamber structure. I also regard the branching tubes, whether joined at the rear or not, as of peculiar advantage because affording a relatively large amount of burner length in the restricted space availed of. These burners 29 are supplied by branch pipes 34 from a pipe 35 leading across the front of the furnace base as here shown, and having a valve 36 to control the supply of gas to both burners. It will be apparent that other arrangements of the pipes or controlling means may be used as conditions may require. The pipes 34 lead in through the openings 28 into the mixers 31 which are just inside the opening and thus receive a plentiful supply of air through these openings 28.

In addition to the openings 28, I prefer to provide sight and auxiliary air openings through short tubes 37, 38 and 39 that extend at intervals approximately in radial directions through the outer wall of the chamber 20 at the bottom and the adjacent wall of the casing 16. Thus, air may pass through these tubes to the interior of the bottom of the chamber 20 from the inside of the casing, but is kept distinct from the air in the air-spaces 25 between the chambers 20 and the sides of the casing 16. Also, these tubes 37, 38 and 39 permit one to look into the bottom of the chamber 20 with the aid of a suitable lighting means inserted therein; so that the condition of the burner 30 and the adjacent parts of the chamber may be inspected conveniently at any time without taking the furnace apart. This is a highly desirable provision because a combustion chamber of any furnace should be frequently inspected to insure that it is not burned out or clogged, or otherwise deranged, so as to be inefficient and dangerous to the rest of the furnace structure. For the purpose of preventing the entrance of

small animals or other objects, each one of the pipes 37, 38 and 39 should be provided with a suitable screen 40; which, as here shown, is preferably provided at the outer 5 end of the tube which opens through the wall of the casing 16, and is removable from the tube.

The interior of each chamber 20 above the burner 30 is provided with an ascending 10 series of baffles 41, 42 and 43 each extending across the full width of the chamber interior, the first extending entirely to the front 21 but ending short of the rear end 22 of the chamber, leaving an upward passage 44; the next baffle 42 meeting the rear end 22 but ending short of the front end 21 and leaving an upright passage 45; and the next baffle 43 being arranged like the first one 41 so that there is an upright passage 46 at the rear. In each chamber 20 above its uppermost baffle 43 at the front end 15 on the inner side is the outlet opening 47, and flues 48 curve inwardly and upwardly and then extend straight upwardly at the 20 respective sides of the fuel-intake 6 of the furnace and communicate through openings 49 in the bottom of the large outer annular part 13 of the radiator 8 with the interior of said part at opposite sides of the forwardly extending flue 12 of this radiator.

With this construction and burning the gas in the lowermost part of the chamber 20, the products of combustion will pass rearwardly in this lowermost part, up 35 through the passage 44 forwardly and up through the passage 45 rearwardly, and up through the passage 46 and finally out through the outlet 47 and up through the flue 48 to the radiator 8, where they must 40 pass around the respective side of the large outer annular part 13 to the final outlet or flue 14 at the rear.

It will thus be seen that when coal or other solid fuel is burned in the fire-pot 4 and gas 45 is burned in the chambers 20 at the same time, the products of combustion from both kinds of fuel pass along together around the radiator 8 and out through the flue 14.

When it is desired to use solid fuel alone 50 without gas, it is desirable to close the communication between the path of the products of combustion from the solid fuel and the unheated air spaces in the unused chambers 20; because the opening of the bottom of any 55 flue to the entrance of cold air decreases its efficiency. Accordingly, I provide means for temporarily closing the upper ends of the flues 48 where they enter the radiator 8. As here shown, this means consists of a 60 segmental flat plate 50 lying on the bottom of the annular part 13 of the radiator 8 and fitting it loosely so as to be slidable there-around and having in its middle a relatively long and wide curved slot 50' so proportioned and arranged that when the plate 50

is slid around in one direction it leaves one of the flues 48 outside the limits of the plate and the other one within the limits of the large slot 50' (Fig. 3); but so that when the plate is slid around in the other direction, unslotted end parts 50" cover the respective flues 48 (Fig. 4.) This plate has a forwardly and upwardly projecting lug 51 at its front side near one end of its slot 50' which is accessible through the clean-out 70 opening 9 of the radiator 8; and preferably projects somewhat into this opening 9, so that in striking one side or the other of the opening, the movement of the plate or damper 50 in either direction is properly limited to accomplish the purpose for which the movement is effected.

For the same reasons as just set forth, it is desirable to cut off the interior of the solid-fuel-burning part of the furnace from 85 the path of the products of gas combustion when the gas-burning part of the furnace only is used. For this purpose, I prefer to provide a damper in the form of a door 52 hinged at one side of the front opening of 90 the short flue 12 to swing horizontally to one side, as shown in Figs. 3 and 4, or to swing around and close the flue 12, as shown in Fig. 1.

In certain cases it is also desirable when 95 either part of a furnace is unused, to not have any of the air circulate other than adjacent to the part being used. To provide for such control of the distribution of the air, I prefer to hinge to the extreme rear 100 corners of the chambers 20, gates or dampers 53 to swing horizontally from positions where they meet across the passage 23 to positions where they lie out against the sides of the cold-air inlet duct 19 inside thereof 105 (Fig. 4); or to be adjusted to a position intermediate of these two positions (Fig. 3.) To better permit these dampers or gates 53 to control this distribution in some instances, I prefer to provide a partition 54 extending 110 across the passage 23 from the dampers or gates 53 up to the tops of the chambers 20. For conveniently adjusting these gates or dampers 53, a horizontally swinging crank 55 extends through the top of the duct 19. 115 It is connected by a single link 56 and diverging links 57 to short inwardly extending arms 58 on the respective gates or dampers 53, which have their upper corners cut away to pass under the links 57 when the 120 gates or dampers are closed.

It will be understood that the relative proportions of the cold-air ducts 19 vary in different installations as may also the proportions of the casing 16 or other parts; 125 so that the means regulating the distribution of cold air may be considerably modified, or details thereof omitted in view of such changed conditions.

When the furnace is to be used for burn- 130

ing coal or other solid fuel only, all that is necessary is to close the damper 50, by opening the door 10 and inserting a poker or other instrument and engaging the lug 51 to slide the damper 50 to the left into the position shown in Fig. 4; and if the door 52 has been closed, opening it by engaging it with the same instrument. Then, if desired, swing the gates or dampers 53 in the cold-air duct outwardly as shown in Fig. 4 by pulling forward on the handle of the crank 55 at the top of the cold-air duct 19. The furnace is now ready for use the same as any coal or other solid-fuel-burning furnace, the clean-out door 10 having been closed.

The smoke and other heated products of combustion will now pass out through the parts 11, 12, 13 and 14 without being retarded by any eddy currents or cold-air entrance: the same as with any furnace having such an arrangement of the radiator. Also, with the gates or dampers 53 thrown out, direct communication between the cold-air duct 19 and the outer air spaces 25 outside the unheated chambers 20 will be prevented and practically the full amount of air from the duct 19 will pass to the spaces 24 around the heated solid-fuel-burning part of the furnace and up around the radiator 8 and out through the warm-air pipes 18.

If it be desired to burn gas while also burning the solid fuel, the damper 50 may be opened by sliding it to the right by means of an instrument after opening the door 10 of the clean-out opening 9; and by adjusting the gates or dampers 53 to mid-positions, as shown in Fig. 3, part of the cold air may be made to pass to each one of the spaces 24 and 25 at each side of the furnace; that passing to the space 24 between the solid fuel-burning and the gas-burning parts being heated from both sources and that passing to the outer space 25 being heated by the gas-burning part. All of the air thus heated, of course, is also heated by the radiator 8 which now has passing through it the products of combustion from both the solid fuel and the gas.

Where the gas alone is to be burned, the damper 50 is opened and the door or damper 52 closed. Also the gates or dampers 53 may be closed so that practically all of the air from the duct 19 passes to the outer spaces 25; or such adjustment may be made as permits a proper proportion of the cold air to pass along the inner sides of the chambers 20. In most instances no appreciable change in adjustment will be needed from that used when both the gas and solid fuel are burned; but when solid fuel only is burned, it is generally more important not to permit any considerable proportion of the cold air to pass outside the chambers 20

away from the heated solid-fuel-burning part of the furnace.

My invention is especially useful in severe climates where during certain periods it is necessary to burn all kinds of fuel available. In some places, at certain times, the supply of gas is insufficient and at other times the supply of coal or other solid fuel insufficient. By having a single apparatus adapted to efficiently burn either kind of fuel alone, or both together, the apparatus may be used in one way or the other as conditions warrant. If solid fuel is preferred, it may be used when the weather is mild, and supplemented with gas during low temperatures; or vice versa.

When the furnace is not in use at all, as in warm weather, both dampers 50 and 52 should be closed, thereby preventing the passage of dampness down from the chimney into the combustion chambers. Since these dampers may be made to fit rather closely they will thus form an effective means of keeping out the dampness, which if permitted to enter during the long period of disuse, causes the insides of the combustion chambers and the grate and burners to rust.

By having the dampers 50 and 52 both inside the radiator without any manipulating means extended out through the walls of the radiator, but accessible through the clean-out opening 9 by opening the door 10 of this clean-out opening, which at all other times is, of course, tightly closed, it is possible to have all the passages for the fumes and other products of combustion unimpaired in their function to conduct these fumes and products to the outer air without allowing any of them to leak out into the air in the casing 16.

While certain constructional details are deemed preferable in connection with my invention and I have shown and described these rather specifically in elucidating the construction and use of my invention as is required, I do not wish to be understood as being limited to such precise showing and description, but having thus fully described my invention, what I claim as new and desire to secure by Letters Patent is:

1. In a stove or furnace, a plurality of combustion chambers separated from each other, whereby an air space is left between adjacent ones of said chambers, means for burning solid fuel in one of said chambers, means for burning fluid fuel in another one of said chambers, each one of said chambers having a passage for the conduction of combustion products therefrom, exclusive of any passage directly between said chambers, a casing inclosing an air space around said chambers and around said air space that is between said chambers, and having an air

- inlet to said spaces and an air outlet from said spaces, and means for reducing passage of air from said inlet to said air space around said chambers without reducing passage of air from said inlet to said air space between said chambers.
2. In a stove or furnace, a plurality of combustion chambers separated from each other, whereby an air space is left between adjacent ones of said chambers, means for burning solid fuel in one of said chambers, means for burning fluid fuel in another one of said chambers, each one of said chambers having a passage for the conduction of combustion products therefrom, exclusive of any passage directly between said chambers, means to stop the conduction of said products of combustion through either one of said passages, a casing inclosing an air space around said chambers and around said air space that is between said chambers, and having an air inlet to said spaces and an air outlet from said spaces, and means for reducing passage of air from said inlet to said air space around said chambers without reducing passage of air from said inlet to said air space between said chambers.
3. In a stove or furnace, a plurality of combustion chambers each having an outlet for combustion products, and separated from each other whereby an air space is left between adjacent ones of said chambers, means for burning solid fuel in one of said chambers, means for burning fluid fuel in another one of said chambers, means common to said plurality of chambers for conducting combustion products from said chambers, means to control the conduction of said products from the respective chambers, a casing inclosing said chambers and said air space and having an air inlet and an air outlet, and a single means for varying the proportions of air passing from said inlet to the respective air spaces.
4. In a stove or furnace, a plurality of combustion chambers each having an outlet for combustion products, and separated from each other whereby an air space is left between adjacent ones of said chambers, means for burning solid fuel in one of said chambers, means for burning fluid fuel in another one of said chambers, a casing inclosing said chambers and said air space and having an air inlet and an air outlet, and having sides spaced away from said chambers, leaving an air space between a side of said casing and the adjacent one of said chambers, inclosed by said casing, and a single means for varying the proportions of air passing from said inlet to the respective air spaces.
5. In a stove or furnace, a plurality of combustion chambers each having an outlet for combustion products, and separated from each other whereby an air space is left between adjacent ones of said chambers, means for burning solid fuel in one of said chambers, means for burning fluid fuel in another one of said chambers, a radiator above one of said chambers, having an outlet for combustion products and having a clean-out opening and means to close said opening, conducting means to conduct combustion products from the respective chambers into said radiator, and a damper for one of said conducting means, in said radiator and accessible through said clean-out opening.
6. In a stove or furnace, a plurality of combustion chambers each having an outlet for combustion products, and separated from each other whereby an air space is left between adjacent ones of said chambers, means for burning solid fuel in one of said chambers, means for burning fluid fuel in another one of said chambers, a radiator above one of said chambers, having an outlet for combustion products and having a clean-out opening and means to close said opening, conducting means to conduct combustion products from the respective chambers into said radiator, and dampers for the respective conducting means, accessible through said clean-out opening.
7. In a stove or furnace, a plurality of combustion chambers each having an outlet for combustion products, and separated from each other whereby an air space is left between adjacent ones of said chambers, means for burning solid fuel in one of said chambers, means for burning fluid fuel in another one of said chambers, a radiator above one of said chambers, having an outlet for combustion products and having a clean-out opening and means to close said opening, conducting means to conduct combustion products from the respective chambers into said radiator, one of said conducting means having an opening into said radiator near said clean-out opening, a damper to close this opening of this conducting means, and engaging means projecting from said damper into said clean-out opening and engaging one or the other side thereof to limit the movement of said damper, and to be engaged through said clean-out opening for moving said damper.
8. In a stove or furnace, a solid-fuel combustion chamber, a radiator comprising a hollow central part into which the upper part of the interior of said combustion chamber opens, and a hollow outer circuitous part communicating with said central part and having an outlet remote from where it thus communicates, and overlying a space around said combustion chamber, and fluid-fuel-combustion chambers flanking said solid-fuel-combustion chamber and spaced therefrom, in said space, and spaced downward from said radiator, and extend-

ing around one side of said solid-fuel-combustion chamber and spaced apart at said side, and each communicating with the interior of said circuitous part of said radiator where it communicates with said central part of said radiator.

9. In a stove or furnace, a solid-fuel-combustion chamber, a radiator comprising a hollow central part into which the upper part of the interior of said combustion chamber opens, and a hollow outer circuitous part communicating with said central part and having an outlet remote from where it thus communicates, and overlying a space around said combustion chamber, fluid-fuel-combustion chambers flanking said solid-fuel-combustion chamber and spaced therefrom, in said space, and spaced downward from said radiator, and extending around one side of said solid-fuel-combustion chamber and spaced apart at said side, and each communicating with the interior of said circuitous part of said radiator where it communicates with said central part of said radiator, and means in said radiator to control the conduction of combustion products from the respective chambers into said radiator.

10. In a stove or furnace, a solid-fuel-combustion chamber, a radiator comprising a hollow central part into which the upper part of the interior of said combustion chamber opens, and a hollow outer circuitous part communicating with said central part and having an outlet remote from where it thus communicates, and overlying a space around said combustion chamber, fluid-fuel-combustion chambers flanking said solid-fuel-combustion chamber and spaced therefrom, in said space, and spaced downward from said radiator, and extending around one side of said solid-fuel-combustion chamber and spaced apart at said side, and each communicating with the interior of said circuitous part of said radiator where it communicates with said central part of said radiator, said radiator having

a clean-cut opening in the radially outer side of said circuitous part near where it communicates with said central part, and means to close said opening, and means in said radiator, accessible through said clean-out opening, to control the conduction of combustion products from the respective chambers into said radiator.

11. In a stove or furnace, a plurality of combustion products from the respective for combustion products, means for burning solid fuel in one of said chambers, means for burning fluid fuel in another one of said chambers, a casing inclosing said chambers and having an air inlet and an air outlet and having sides spaced away from said chambers, leaving an air space between a side of said casing and said chamber in which is the means for burning fluid fuel, and a conducting means through said casing side across said air space into this chamber, permitting access to said means for burning fluid fuel.

12. In a stove or furnace, a central solid-fuel-combustion chamber, having access means at its front and having an outlet for combustion products, a casing inclosing said chamber at the sides and rear thereof and around said access means, leaving lateral and rear spaces inside said casing, and having an air inlet and an air outlet, and fluid-fuel-combustion chambers in said spaces and communicating with said outlet of said solid-fuel-combustion chamber, and having their fronts against the inner surfaces of the front sides of said casing at opposite sides of said access means, and said fronts and sides having access openings through them to the interiors of said fluid-fuel-combustion chambers, but these chambers being spaced away from said casing sides to the rear of these access openings.
